[57] CLAIM

The ornamental design for an electrical connecting plug, as shown and described.

DESCRIPTION

FIG. 1 is a front elevation view of an electrical connecting plug showing my new design;

FIG. 2 is a rear elevation view thereof;

FIG. 3 is a top plan view thereof;

FIG. 4 is a bottom plan view thereof;

FIG. 5 is a left side view thereof;

FIG. 6 is a right side view thereof;

FIG. 7 is a front elevation view of an electrical connecting plug showing a second embodiment of my new design;

FIG. 8 is a rear elevation view thereof;

FIG. 9 is a top plan view thereof;

FIG. 10 is a bottom plan view thereof;

FIG. 11 is a left side view thereof; and,

FIG. 12 is a right side view thereof.
